UNITED STATES PATENT OFFICE

CHARLES H. KESTENMAN, OF PROVIDENCE, RHODE ISLAND, ASSIGNOR TO KESTENMAN BROS. MFG. CO., OF PROVIDENCE, RHODE ISLAND, A CORPORATION OF RHODE ISLAND

DESIGN FOR A WRIST WATCH STRAP OR SIMILAR ARTICLE

Application filed December 21, 1931. Serial No. 42,168. Term of patent 14 years.

To all whom it may concern:

Be it known that I, CHARLES H. KESTENMAN, a citizen of the United States, residing at 108 Miller Avenue, in the city of Providence, county of Providence, and State of Rhode Island, have invented a new, original, and ornamental Design for a Wrist Watch Strap or Similar Article, of which the following is a specification, reference being had to the accompanying drawings, forming a part thereof, in which:

Fig. 1 is a plan view of a wrist watch strap embodying the new design; and

Fig. 2 is a sectional view of the strap shown in Fig. 1.

I claim:

The ornamental design for a wrist watch strap or similar article substantially as shown.

CHARLES H. KESTENMAN.
